(57) CLAIM

The ornamental design for a karaoke stand, as shown and described.

DESCRIPTION

FIG. 1 is a perspective view of a karaoke stand embodying the present invention;

FIG. 2 is a front view of the karaoke stand of FIG. 1;

FIG. 3 is a left side view of the karaoke stand of FIG. 1, the right side view being a mirror image thereof;

FIG. 4 is a top view of the karaoke stand of FIG. 1; and, FIG. 5 is a rear view of the karaoke stand of FIG. 1.

The broken line showing of the environment is for illustrative purposes only and forms no part of the claimed design. The bottom view forms no part of the claimed design.

1 Claim, 4 Drawing Sheets
